Primary Examiner — Khawaja Anwar*Assistant Examiner* — Julice Seung Eun Oum(74) *Attorney, Agent, or Firm* — Ware Fressola Maguire & Barber LLP(57) **CLAIM**

The ornamental design for an exercise device, as shown and described.

DESCRIPTION

FIG. 1 is a front, right side perspective view of an exercise device showing my new design;

FIG. 2 is a rear, left side perspective view thereof;

FIG. 3 is a top, rear perspective view thereof;

FIG. 4 is a bottom, left side perspective view thereof;

FIG. 5 is a front elevational view thereof;

FIG. 6 is a rear elevational view thereof;

FIG. 7 is a left-side elevational view thereof;

FIG. 8 is a right-side elevational view thereof;

FIG. 9 is a top plan view thereof; and,

FIG. 10 is a bottom plan view thereof.

The broken lines shown in the drawings represent portions of the exercise device and form no part of the claimed design.

1 Claim, 10 Drawing Sheets
